UNITED STATES PATENT OFFICE.

GEORGE BENEDETIC McCORMACK, OF CHICAGO, ILLINOIS, ASSIGNEE OF ONE-HALF TO
SHUFORD BRADFORD MARKS, OF CHICAGO, ILLINOIS.

EYEGLASS CLEANER.

Application filed February 11, 1927, Serial No. 167,415. Renewed February 6, 1929.

My invention has for its main object the provision of a device for quickly, conveniently, and effectively cleaning eye-glasses of the usual type, the device being preferably 5 such that it is conveniently carried in a person's clothes pocket and that it can be held and operated with one hand of the operator, the other hand of the operator being free for holding the eyeglasses during the cleaning 10 operation.

Another object resides in the provision of an advantageous structure whereby the cleaning element of the cleaner may be easily and quickly mounted on and dismounted 15 from the cleaner with a view toward facilitating renewal of the cleaning element.

With these objects in view my invention consists in certain features of novelty in the construction, combination, and arrangement of parts by which the said objects and certain other objects, hereinafter appearing, are effected, all as fully described with reference to the accompanying drawing and more particularly pointed out in the appended 25 claims.

In said drawing—

Figure 1 is a top plan view of an eyeglass cleaner embodying my invention;

Figure 2 is a side elevation of the same;

Figure 3 is a view similar to Figure 1 with certain parts removed;

Figure 4 is a section of the cleaner on the line 4—4 of Figure 3;

Figure 5 is a top plan view of the supporting disk, hereinafter described;

Figure 6 is an enlarged partial section on the line 6—6 of Figure 5;

Figure 7 is a side elevation of the cleaning element and attached mounting disk with the peripheral portion of the cleaning element flexed away from the mounting disk to show the peripheral portion of the mounting disk free of the cleaning element as hereinafter described.

Like characters of reference indicate like parts in the several views.

Referring to the drawings 1 designates a hollow casing or frame which is of shallow circular formation. Secured on the bottom 50 of the casing and extending upwardly within the casing in coaxial relation therewith is a stud 2, and rotatably mounted on this stud within the casing is a hub 3 having a relatively small spur pinion 4 formed thereon. See Figures 3 and 4. Secured at the upper

end of the hub 3 in coaxial relation therewith and with the casing is a support disk 5 which has a diameter slightly less than the internal diameter of the casing. This disk is disposed at the opening of the casing and 60 forms a closure for the same.

Another stud 6 is secured on the bottom of the casing 1 adjacent the periphery thereof and extends upwardly within the casing in parallelism with the stud 2. A lever 7 is 65 pivotally mounted at an intermediate point thereon on the stud 6 within the casing by means of a hub 8, and the inner end of this lever is formed with an internal spur gear segment 9 which meshes with the pinion 4 70 whereby when the lever is oscillated the pinion 4 and with it the support disk 5 is rotated in alternate directions, the gear segment 9 and the pinion 4 constituting multiplying gearing.

A coiled tension spring 11 within the casing has its respective ends secured to the bottom of the casing and to the lever 7 whereby to move the lever 7 in one direction of its pivotal movement. The lever 7 projects exteriorly of the casing through an opening 12 in the peripheral wall of the casing and a finger hold 13 is formed on this exterior portion of the lever for the manual operation thereof. A second finger hold 14 is formed 85 on the casing exteriorly thereof whereby the cleaner may be held in one hand and the lever 7 be intermittently operated against the influence of the spring for rotation of the support disk 5 in alternate directions in an 90 obvious manner. The end of the stroke of the lever 7 to which the spring 11 operates the lever is shown in full lines and the end of the stroke of the lever to which the operator operates the lever against the influence 95 of the spring is shown in dotted lines in Figure 3.

A cleaning element 15 of suitable cleaning material such as cloth is made in the form of a disk approximating the size of the support disk 5 and is thickened at its center portion for the cleaning of the concave surfaces usual in eyeglasses. A mounting disk 16 also approximating the size of the support disk is secured at its center, as indicated at 17 in Figure 7, in a suitable manner as by glue to the underside of the cleaning element 15 in coaxial relation therewith, thus leaving the peripheral portion of the supporting disk free of the cleaning element. The mounting disk 110

16 is made of a stiff material such as cardboard which may be flexed slightly, and the support disk 5 is provided with peripheral lugs 18 spaced about the axis thereof, see Figures 4, 5, and 6, which are adapted for engagement about the periphery of the mounting disk and between peripheral portions of the mounting disk and the cleaning element 15 and independently of the cleaning element 10 for detachably securing the cleaning element on the supporting disk. Thus, the attaching means, by reason of the engagement of the lugs 18 with the peripheral portion of the mounting disk 16 independently of the cleaning element 15, does not interfere with the use of the entire outer surface of the cleaning element for cleaning, and when the cleaning element is worn or dirty it may be easily and quickly replaced by a new cleaning element.

20 In cleaning eyeglasses the operator holds the cleaner, by means of two fingers of one hand being engaged in the finger holds 13 and 14, and intermittently operates the lever 7 against the influence of the spring 11 for rotating the cleaning element 15 in alternate directions while applying the surfaces of the eyeglasses held in the other hand of the operator to the cleaning element.

It is to be observed that the mechanism is 30 effectively enclosed and that the cleaner may be made of a size that may be conveniently carried in the pocket of the user.

While I have herein shown and particularly described the preferred embodiment of my 35 invention I do not wish to be limited to the precise details of construction shown as changes may readily be made without departing from the spirit of my invention, but having thus described my invention, I claim as 40 new and desire to secure by Letters Patent the following:—

1. In a cleaner of the character described

the combination with a revoluble supporting disk, of a cleaning element disk, a stiff mounting disk secured at its center to said cleaning element disk in coaxial relation therewith, and means on said supporting disk and engageable with the peripheral portion of said mounting disk independently of said cleaning element disk for detachably securing said 50 cleaning element disk on said supporting disk.

2. In a cleaner of the character described the combination with a revoluble supporting disk, of a cleaning element disk, a stiff mounting disk capable of flexure and secured at its 55 center to said cleaning element disk in coaxial relation therewith, and a plurality of lugs on said supporting disk and spaced about the axis thereof and adapted for engagement about the periphery of said mounting disk 60 and between the mounting disk and said cleaning element disk for detachably securing said cleaning element disk on said supporting disk.

3. In an eyeglass cleaner the combination 65 with a hollow casing of shallow circular formation, of a supporting disk disposed at the opening of the casing in coaxial relation therewith and carried by the casing for axial rotation with respect thereto, a cleaning element disk, a relatively stiff mounting disk capable of flexure and secured at its center 70 to said cleaning element disk in coaxial relation therewith, and a plurality of peripheral lugs formed on said supporting disk and 75 spaced about the axis thereof and adapted for engagement about the periphery of said mounting disk and between the mounting disk and said cleaning element disk for detachably securing said cleaning element disk on said supporting disk.

In witness whereof I hereunto affix my signature this fifth day of February, 1927.
GEORGE BENEDICT McCORMACK.
